US00D970846S

(12) **United States Design Patent** (10) **Patent No.:** **US D970,846 S**
Chen (45) **Date of Patent:** **** Nov. 22, 2022**

(54) **SAFE BOX**

(71) Applicant: **Sheng Chen**, Ningbo (CN)
(72) Inventor: **Sheng Chen**, Ningbo (CN)
(**) Term: **15 Years**
(21) Appl. No.: **29/836,778**
(22) Filed: **Apr. 28, 2022**
(51) LOC (13) Cl. **99-00**
(52) U.S. Cl. **USPC D99/28**

(58) **Field of Classification Search**

Primary Examiner — Elizabeth J Oswecki

(57) **CLAIM**

The ornamental design for a safe box, as shown and described.

DESCRIPTION

FIG. 1 is a perspective view of a safe box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the safe box that form no part of the claimed design.

1 Claim, 8 Drawing Sheets
